WRAPPING MACHINE

Harry E. Townsend, Brooklyn, N. Y.

Application September 19, 1931, Serial No. 563,817

8 Claims. (Cl. 93—7)

My invention relates to machines for handling and wrapping articles, and has special reference to a machine for wrapping small articles such as candy tablets, thin bars of chewing gum or other confection, or a plurality of such articles.

5 An object of my invention is to provide a machine of this character which is simple in construction and rapid and efficient in operation.

Another object is to provide a machine for 10 wrapping articles that are relatively thin in one direction in a novel and improved manner.

Another object is to provide a machine adapted 15 to wrap and seal, in a novel and efficient manner, articles or a row of articles, having ends that are neither rectangular nor square.

Another object is to provide a machine for 20 wrapping articles having shapes as above described that is equally well adapted for wrapping articles having ends that are rectangular or square.

The several features of the invention, whereby 25 these and other objects are attained, will be clearly understood from the following description and accompanying drawings, in which:

Figure 1 is a front end elevation of the machine embodying my invention;

Figs. 2a and 2b are elevational views of the 30 left hand side of the machine. These two views shown separately on account of scale considerations, should be imagined as joined one to the other to afford a complete view of the machine;

Fig. 3 is a right hand elevational view of the machine with un-essential details omitted;

Fig. 4 is a vertical sectional detail on the line 35 4—4, Fig. 1;

Fig. 5 is a horizontal sectional detail of the 40 magazine taken on the line 5—5, Fig. 4;

Fig. 5a is a detail showing a part of the pusher for pushing a row of candies out of the magazine;

Figs. 5b and 5c are detail views, partly in section, showing modifications of the article holding magazine;

Fig. 6 is a vertical sectional detail on the line 45 6—6, Fig. 7;

Fig. 7 is a detail, on the line 7—7, Fig. 1, partly in section, showing the gears for driving the wrapper feed rolls and a part of the wrapper shearing mechanism as viewed from the right hand side of the machine;

Fig. 8 is a plan detail, partly in section, showing two of the wrapping heads and their drive gears;

Fig. 9 is a sectional detail on the line 9—9, 50 Fig. 8;

Fig. 10 is a sectional detail on the line 10—10, Fig. 8;

Fig. 11 is a detail showing four of the fingers that push the package from one wrapping head into the next;

Fig. 12 is a vertical sectional detail, partly diagrammatic, through four of the wrapping mechanisms of the machine;

Fig. 13 is a vertical sectional view on the line 13—13, Fig. 2a, showing the heater mechanism 10 with certain parts shown in section;

Fig. 14 is a detail showing part of the mechanism for folding the wrapper over the ends of the package as viewed from the left hand side of the machine;

Fig. 14a is a vertical sectional detail on the line 14a—14a, Fig. 2a;

Fig. 15 is a vertical sectional detail on the line 15—15, Fig. 2b;

Fig. 16 is a detail, partly in section, showing 20 the labeling mechanism and a part of the mechanism for holding the packages under pressure after they have passed through the heater mechanism, as viewed from the left hand side of the machine;

Fig. 17 is an elevational detail of the labeling device, with the gear housing shown in section, as viewed from the right hand side of the machine;

Fig. 18 is a detail of a part of the package pressing mechanism viewed as indicated at the line 18—18, Fig. 16;

Fig. 19 is a detail of a part of the labeling mechanism shown partly in section on the line 19—19, Fig. 16;

Fig. 19a is a sectional detail on the line 19a—19a, Fig. 19;

Fig. 20 is a vertical sectional detail on the line 20—20, Fig. 16, showing part of the labeling mechanism;

Figs. 21, 22, 23 and 24 are illustrations of articles the machine is adapted to wrap;

Figs. 25 to 33 inclusive illustrate various steps in winding and folding the wrapper about a row of articles;

Fig. 34 is a vertical sectional view on the line 34—34, Fig. 2a;

Fig. 35 is a horizontal sectional view on the line 35—35, Fig. 34;

Fig. 36 is a detail showing the clutch and gears 50 by means of which the article and wrapper feeding mechanisms may be thrown out of operation while the rest of the machine continues to operate;

Fig. 37 is another view of the mechanism illus- 55

trated in Fig. 36, viewed from the direction indicated by the arrow in Fig. 36; and

Fig. 38 is a sectional detail on the line 38—38, Fig. 37.

5 The machine hereinafter described, as one embodiment of my invention, is adapted to wrap a row of substantially flat circular disks, such as hard candies or the like, as illustrated in Fig. 21 or, with but slight change, to wrap a plurality of 10 rectangular articles as shown in Fig. 22, a thin rectangular bar as shown in Fig. 23, or a plurality of rectangular bars as shown in Fig. 24. The machine will first be particularly described as adapted for wrapping the circular disks or candies illustrated in Fig. 21.

As it is very desirable to thoroughly protect certain varieties of candy that may be wrapped by the machine from atmospheric moisture, the machine has, in the present instance, been designed 20 to wind a waxed paper wrapper twice around the peripheral surface of a row of candies with peripheral portions of the wrapper overlapping, and with the ends of the wrapper projecting a distance beyond the ends of the row. 25 The projecting end portions of the wrapper are closed over the ends of the row by first bending inwardly or crimping the projecting ends on two opposite sides thereof, as shown in Figs. 29 and 30, flattening the projecting ends as shown in Fig. 31, bending downwardly the projecting ends as shown in Fig. 32, laying the downwardly bent ends over against a side of the package as shown in Fig. 33, and by securing the bent over ends of the wrapper against the side of the package by 30 heat sealing or by the application of a band or label.

Referring to the drawings the right and left frames, designated by the numerals 2 and 4 respectively, provide bearings for the various cam 40 shafts and a support for the table 6 bolted thereto. Bolted to the upper face of the table is an upright frame 8 carrying a magazine for holding the candies, a roll of wrapping material, wrapper feeding mechanism, a pair of shear knives and 45 a support for the candies in the magazine.

As shown in Figs. 1, 4 and 5, the magazine comprises, in the present instance, three seamless steel tubes 10, brazed or soldered in vertical position to the support bar 12, secured to the bracket 50 13, which is bolted to the frame 8. The tubes 10 have diameters slightly larger than the diameters of the candies and have slots or openings 14 cut in their outer faces to facilitate charging the magazine with the candies. As the tubes 10 are open at their lower as well as their upper ends, a plate or shelf 16, fastened to the bracket 18, bolted to the frame 8, provides a support for the candies in the said tubes.

The bracket 8 is provided at its upper end with 60 a bearing for the stud shaft 20 on which is mounted for rotary movement the spool 22 carrying the roll of wrapping material 24. The spool and roll are prevented from over-running by any suitable friction device 25 engaging the spool. 65 The web of wrapping material 27 is drawn from the roll and passed downwardly over a suitable guide roll 26 and between the feed rolls 28 and 30. The feed roll 28 has one end of its shaft journaled in the frame 8 and the other in the bracket 70 32, rigidly secured on the ends of the stud shafts 34 and 36, the opposite ends of which are rigidly secured in the frame 8. The feed roll 30 is journaled in the arms 38 and 40 mounted for swinging motion on the stud shaft 36. The upper ends of 75 the arms 38 and 40 are provided with bearings for

the rock shaft 42 to which are rigidly secured the hand-operated levers 44. The links 48 are pivotally connected at one end mid-way of levers 44, and at the other end are pivotally connected to the bell cranks 50, pivotally mounted on the stud 52 secured in the frame 8, and the stud 54 secured in the bracket 32. Coiled springs 58 tend to turn the bell cranks 50 in a counter-clockwise direction, viewing Figs. 2b and 4. With this construction, when either of the hand operated levers 44 is swung downwardly into the position shown, the links 48 are positioned below the pivotal bearings of rock shaft 42, which permit the springs 58 to act through the bell cranks 50, links 48 and levers 44 to turn the arms 38 and 40 in a direction to press the movable roll 30 toward the other roll 28. A laterally projecting pin 60 on each of the levers 44 enters a notch on the under side of the links 48 to lock the links and levers together in the position shown. The feed rolls may be 20 separated by merely swinging upwardly either of the hand-operated levers 44.

The shaft of the roll 28 projects through the frame 8 and has secured to its projecting end the pinion 62, as best shown in Figs. 6 and 7. The 25 shaft of the feed roll 30 projects a considerable distance beyond the supporting arm 40, passing behind the frame 8, so that a pinion 64 secured to its outer end is in line with the pinion 62. These pinions are smaller in diameter than the 30 diameters of the feed rolls, so that when the feed rolls are engaged the teeth of the pinions do not touch. The stud shafts 34 and 36 project a distance through the frame 8 and have their projecting ends turned to a smaller diameter to provide 35 bearings for the idler gears 66 and 68.

The brackets 13 and 18 Figs. 1 and 2b, provide bearings for the rack 70, which is given vertically reciprocating motion by the links 72, bell crank 74 mounted on the shaft 75, cam roll 76 40 and cam 78 secured to the shaft 80. A gear 82, Figs. 6 and 7, secured to one end of the shaft 84 meshes with the rack 70, and is thereby rotated alternately in opposite directions, one full revolution. To the other end of the shaft 84 is secured an arm 86 carrying a stud 88 on which is mounted a pawl 90. A gear 92, meshing with the idler gear 68, is mounted loosely on the shaft 84 and is riveted to the ratchet 94. This ratchet has a single tooth or notch adapted to be engaged by 50 the pawl 90, and it will be evident from an inspection of Figs. 6 and 7, that as the rack 70 moves upwardly the pawl 90 will engage the ratchet 94 and cause it to make one full revolution in a clockwise direction, viewing Fig. 7. This 55 rotary motion of the ratchet is transmitted through the gears 92, 68 and 66 and pinions 62 and 64 to the feed rolls 28 and 30, causing them to make one full revolution in a direction to feed the web of wrapping material downwardly. The 60 diameters of the feed rolls are such that at one revolution they feed just enough wrapping material for one wrapper. It will be evident that as the rack 70 moves downwardly the pawl 90 will ride on the ratchet 94 without imparting motion thereto. As the web of wrapping material is fed downwardly it is guided between the blade 96, and shear knife 98, by the guide bars 100 and 102, secured in vertical position in the support bars 104 and 106, secured to the bracket 108 65 which is bolted to the frame 8.

The stationary shear blade 96 is rigidly secured to the bracket 108. The co-operating blade or knife 98 (Figs. 1, 4 and 7) extends through an opening 99 in the frame 8 and is secured to the 75

upper end of a vertical pivot pin 110 which extends downwardly through a bearing block 112 secured to the right hand side of the frame 8. The lower end of the pivot pin is threaded and provided with two lock nuts 113. A spring 114 coiled about the threaded portions of the pivot pin and having its lower end resting on the bracket 115, and its upper end pressing against the under side of the lower lock nut, urges the pivot pin 110 and consequently the shear knife 98 upwardly, and causes the knife to press closely against the shear blade 96. To the right hand end of the shear knife 98 is attached a roll 116 engaged by the forked lever 118 secured to one end of the rock shaft 120 having bearings in the bracket 122. To the other end of the rock shaft 120 is secured an arm 124 provided at its lower end with a cam roll 126 working in a groove in a cam 128 secured to the shaft 80. The cam 128, acting through the connections above mentioned, gives operative motion to the knife 98 to shear a section of wrapping material from the web after the correct length of web has been fed downwardly by the feed rolls 28 and 30. During the cutting off movement of the shear knife 98, the upper end of a screw 130 rides on an inclined surface 132 on the lower end of the bearing block 135 secured to the bracket 137, so as to tend to cause clearance at the right hand end of the blades, thus permitting cutting pressure at the left hand end of the blades.

Bolted to the upper face of the table 6 are two parallel frames 134 and 136, shown in Figs. 1, 2a, 2b, 3 and 8. These frames provide bearings for the shafts on which are mounted the mechanisms that wind and fold the wrappers about the candies, and the mechanisms for sealing the packages thus formed. The first of these mechanisms, best shown in Figs. 8, 9 and 10, will now be described.

To one end of the shaft 138 is rigidly secured the head casting 140 having four projections or lugs 142. To each of these lugs are bolted the ends of two over-hanging bars 144 and 146, spaced apart by the blocks 148. Yieldably connected to each of the bars 144 are three short bars or plates 150. The manner of attaching these plates is best shown in Fig. 9. Four shouldered studs 151 are riveted to each of the plates 150, each of the studs having a tapped hole in its upper end to receive the button head screw 152. Springs 154 tend to push the plates 150 away from the bars 144, and toward the bars 146, the movement of the plates 150 being limited by the heads of the screws 152 whereby the plates 150 and bars 146 are spaced a suitable distance apart to provide between them channels 155 for the articles to be wrapped and their wrappers. The head casting 140, and the above mentioned parts carried thereby, constitute the first wrapper winding mechanism, which is designated in the drawings by the letter A, Figs. 2b, 4, 8 and 9. For convenience, this and similar mechanisms will be hereinafter referred to simply as wrapping heads.

The right hand end of the shaft 138 projects a short distance outwardly beyond the frame 136 and has rigidly secured thereto a four slotted Geneva wheel 156, with the slots facing the frame 136. Directly below the shaft 138 is another shaft 158 having bearings in the frames 134 and 136. To the outer end of this shaft is rigidly secured a miter gear 160 meshing with the miter gear 162 rigidly secured to the shaft 164. To the shaft 158, between the miter gear 160 and the frame 136, is rigidly secured a Geneva driver and

locking member 166, provided with a roll 168 adapted to enter the slots in the Geneva wheel. It will thus be seen that each time the shaft 164 makes one complete revolution the head 140 is moved through 90° in the direction indicated by the arrow in Fig. 9. It will further be seen that the head moves intermittently, with periods of rest between the periods of movement. The wrapping heads B, C and D, carried by shafts 170, 172 and 174 respectively, are identical with head A except that these heads have a single pressed plate 176, instead of three plates 150 as in head A. The driving members for these heads are also identical with the driving members for the head A, they are driven in the same direction and have the same periods of motion and rest.

To the front end of the table 6 is bolted a bracket 178, providing bearings for the slide 180 to the upper side of which is fastened the pusher plate 182. This slide is given reciprocating motion longitudinally of the machine by the cam 184 through the connections comprising the lever 186 pivotally mounted on the bracket 188, the cam roll 190, and the link 192 connecting the upper end of the lever 186 to a bracket 194 fastened to the underside of the slide.

Bolted to the upper left hand side of the table 6 are three brackets 196, 198 and 200. These brackets provide bearings for the slide bar 202, which is given reciprocating motion longitudinally of the machine by the cam 204, rigidly secured to the shaft 206. This shaft has rigidly secured to its right hand end a miter gear 208, meshing with the miter gear 210, rigidly secured to the shaft 212. The connections through which the cam 204 actuates the slide bar 202 comprise the cam roll 214, the lever 216 pivotally mounted on the frame 4, the link 218, connecting the upper end of the lever 216 to the block 220 rigidly secured to the slide 202. The slide bar has rigidly secured thereto a plurality of pusher bars or fingers 222, 224, 226, 228, 230, 232, 234 and 236, the function of which is to push the partly formed packages from one wrapping head or other rotary mechanism into the next.

Figs. 4 and 5 show the first wrapping head A, the web of wrapping material 27, the shear knife 98 and the pusher plate 182 in their relative positions as the pusher plate is just starting to push the lowermost row of candies from beneath the three stacks in the magazine, into a channel 155 of the wrapping head. The movements of the parts are so timed that as the row of candies reaches the web of wrapping material a section of the material is cut off by the knife and carried by the candies into the channel. As shown in Fig. 4, the lower end of the tubes 10, comprising the magazine, are spaced a distance from the supporting plate 16. This distance is greater than the thickness of one candy but less than the thickness of two. It will be seen therefore, that as the pusher plate 182 pushes forward the lowermost row of candies the next row rests on the pusher plate and will be prevented from forward movement by the lower ends of the tubes, and when the pusher plate is returned to starting position the stacks will drop down on the supporting plate 16. Due to the thickness of the walls of the tubes 10, the stacks of candies there-in are spaced somewhat apart. Before wrapping a row of candies it is desirable to bring the candies together with their edges touching. For this purpose, the pusher plate 182, Figs. 5 and 5a, is made with flaring sides 183, which cause the two end candies in a row to be pushed laterally toward

the middle candy as shown in Fig. 5a. The bar 187 fastened to the bracket 18 prevents upward displacement of the candies as they are pushed from the magazine to the wrapping head.

- 5 The shear blade and its co-operating knife are located at such a distance from the plane of the path of the candies that when the candies and wrapper are pushed into a channel 155 of the wrapping head the wrapper will cover three sides. 10 10 of the row of candies as shown in Fig. 25, with sufficient unused wrapper material 238 projecting out of the channel to make two complete wraps around the candies. After a row of candies and their wrapper have been pushed into a channel 15 of the wrapping head A at station K, as shown in Fig. 4, the head rotates through an angle of 90°, carrying the partly formed package to station L, the feed rolls feed downwardly sufficient wrapper material 21 for another wrapper and. 20 the pusher plate is returned to the starting position, these movements occurring synchronously.

It will be observed that when a row of candies has been pushed into a channel of the wrapping head A and the head rotated to bring the row to the station L, the open mouth of the channel faces downwardly. It is necessary, therefore, to provide means to prevent the candies from falling out of the channel while the channel is at, or is moving to or away from this station. The spring pressed plates 153, Figs. 8 and 9, serve this purpose. Each plate being independently spring pressed, and being of such size as to cover one candy only, each candy in a row is held securely in place, even when there is a considerable variation in the thickness of the individual candies. These plates serve further to cause the wrapper to be tightly drawn around the row of candies as the row is pushed into a channel 155.

It will be observed that when a row of candies 40 and their wrapper have been carried from the station K to the station M by two successive rotary movements of the wrapping head A, the unwound portion 238 of the wrapper hangs downwardly across the mouth of the channel 155, containing the row, and that this channel is in alignment with a similar channel in the head B. It will be seen, therefore, that when the slide bar 202 is moved rearwardly by the cam 204 the pusher finger 222 will push the candies and their wrapper from the channel in the head A into the channel in the head B. This results in the wrapper being wound around two more sides of the row of candies as shown in Fig. 26. As shown in Fig. 26 the wrapper has been wound one full turn around the row of candies, and as the row is moved, by two successive rotary movements of the head B, from the station M to the station P, Fig. 12, the candies and wrapper are prevented from falling out of the channel containing them 60 by the single spring pressed plate 176, which is of sufficient length to bear on all of the candies in the row.

At the station P, the partly formed package that has just been described as having arrived at 65 that station, is pushed by the finger 224 from its channel in the head B, to a similar channel in the head C, causing the wrapper to be further wound about the row of candies as shown in Fig. 27. When the head C has carried the package to the station Q, the finger 226 pushes it into a channel in the head D, completing the winding of the wrapper about the candies as shown in Fig. 28.

Referring to Fig. 11, it will be observed that the pusher fingers 226 and 228 have cut out portions 75 239 leaving rearwardly extending portions 240 and

242 which are V shaped in cross section, as shown in Fig. 12. The object of forming these portions in this manner is to cause them to bend inwardly or crimp the projecting ends of the wrapper as shown in Fig. 11. As the pusher finger 226 pushes a package from the head C to the head D, the projecting ends of the wrapper are crimped on the front side of the package. When the package is moved by the head D to the station R the crimped side of the wrapper will face rearwardly so that when the package is pushed by the finger 228 from the head D to the head E the wrapper on the rearward side of the package will be crimped correspondingly, as shown in Fig. 29.

After a wrapper has been fully wound about a 15 row of candies and the projecting ends of the wrapper crimped as shown in Figs. 29 and 30, it is required to close the projecting ends of the wrapper as shown in Fig. 33. This is done by first flattening the projecting ends of the wrapper as 20 shown in Fig. 31, then bending the flattened end portions downwardly as shown in Fig. 32 and finally, by turning over the flattened end portions against the side of the package as shown in Fig. 33. The mechanism for effecting these operations, which may be designated as wrapping head E, will now be described.

Referring to Figs. 2b, 3, 14, 14a and 15, the head casting 244, the shaft 245 on which it is secured, the gears and Geneva members for driving this 30 shaft are exactly the same as corresponding parts of the first wrapping mechanism designated by the letter A, except that the bevel gear 247, rigidly secured to the shaft 164, is located at the left of its mating gear as viewed in Fig. 3. The object 35 of this arrangement of the gears is to drive the head E in a counter-clockwise direction as viewed in Fig. 14. To each of the four lugs 246 of the head casting 244 are bolted offset bars 248, to the offset ends of which are secured by screws, thin 40 plates 250. Also bolted to the lugs 246 and spaced from the bars 248 by spacers 252, are four other offset bars 254 corresponding in shape to the bars 248. The offset ends of these bars carry spring pressed plates 256, secured to the offset ends of 45 the bars in exactly the same manner as the spring pressed plates in wrapping heads B, C and D. As in the wrapping heads already described, the plates 250 and 256 are spaced apart to provide between them a package receiving channel 251. 50 To frame 134 is bolted a bracket 258 to which is bolted a bar 260. To this bar is bolted two blocks 262 provided at their lower ends with hinge pins 264. Mounted on these pins, for swinging action, are two blocks 266 having riveted thereto two 55 semi-circular plates 268. To the outside of these plates, at their forward ends, are riveted two blocks 270, having their lower faces in about the same plane as the lower faces of the spring pressed plates 256, when the head E is dwelling to receive 60 a package from the head D. The two semi-circular plates 268 are spaced apart a distance approximately equal to the length of a row of candies. This distance may, however, be regulated by the adjusting screws 272, carried by the 65 bar 260 and engaging the pins 274 driven into the blocks 266. A coiled spring 276 connecting the two blocks 266 tends to draw the two semi-circular plates 268 towards each other and cause them to bear with yieldable pressure against the 70 ends of a package as will be more fully described.

A forked member 278 is rigidly secured to the upper end of the vertically reciprocating rod 280 connected by the link 282 to the bell crank 284 provided at its lower end with a cam roll 286. 75

The roll 286 works in a groove in the cam 288, rigidly secured to the shaft 206. The upper ends of the forks of the member 278 have flat smooth surfaces corresponding in size to the underside 5 of the blocks 270 riveted to the forward ends of the semi-circular plates 268. When a partly formed package, as shown in Figs. 29 and 30, is pushed from a channel in the head D, to a channel in the head E, the cam 282 moves the forked member 10 278 upwardly, causing the projecting ends of the wrapper to be flattened and compressed between the upper faces of the forks and the blocks 270. The cam 289 then moves the forked member 15 downwardly out of engagement with the blocks 270 and the head E is rotated in a counter-clockwise direction as shown in Fig. 14. It will be apparent that as the head E rotates in the direction shown the projecting ends of the wrapper will be bent downwardly by the plates 268, which being 20 yieldably spaced, cause the wrapper to be bent on lines coinciding with the ends of the row of candies.

When a package has been carried by the head E to the station S the bent over end portions of the wrapper 292 will project upwardly as shown by dot and dash lines in Fig. 14. It is next required to bend the upwardly projecting portions down against the side of the package, and the mechanism for accomplishing this will now be described. The bell cranks 294 mounted for rocking motion on the brackets 295 have secured to their upper ends thin plates 296 as best shown in Figs. 14 and 14a. These plates 296 are adapted when the upper arms of the bell cranks 294 are moved towards each other, to tuck the upwardly projecting ends of the wrapper 292 over against the side of the package. The bell cranks 294 are given rocking motion through the link 298, Fig. 2a, bell crank 299 pivotally mounted 30 on the bracket 300, cam roll 301 working in a groove in the cam 302 rigidly secured on the shaft 304. This shaft is driven by a miter gear 306, Fig. 3, rigidly secured to its right hand end and meshing with another miter gear 308 rigidly secured to the shaft 212.

It will be observed that the winding of the wrapper about the row of candies was completed when the row was pushed from the channel in the wrapping head C to a channel in the wrapping head D, and that the peripherally overlapping portions of the wrapper are on the underside of the package as shown in Fig. 28. It will be apparent, therefore, that when the package has been carried by the head D to the station R, Fig. 12, the overlapping peripheral portions of the wrapper will be on the upper side of the package, and that when the package has been carried by the head E from the station R to the station S, Fig. 4, and the projecting end portions turned over against the side of the package as described, they will be turned over against the side of the package opposite the overlapping peripheral portions of the wrapper. This is desirable in order to draw the overlapping peripheral portions tightly together where they are bent over the ends of the package. When articles are wrapped in this manner and the bent over projecting ends of the wrapper secured against the side of the package, very good protection is afforded the wrapped articles even without heat sealing the package.

It will be obvious that in some cases it may be desirable to wrap an article or articles in a wrapper of waxed paper, or other material having a waxed surface, and seal the bent over ends

of the wrapper against the side of the package by the application of suitable degrees of heat and pressure. In other cases the use of heat may be objectionable owing to the nature of the articles to be wrapped. In such cases a wrapper of either waxed or un-waxed material may be used, and the bent over ends of the wrapper secured against the side of the package by the application of a band or label. The machine has, therefore, been provided with means whereby articles may be wrapped in either manner. The said means comprise a heater for melting the wax of the wrapper when a waxed wrapper is used, mechanism for holding the package under pressure while the melted wax is cooling, and a device for wrapping a band or label about the package with the ends of the label overlapping and glued or pasted together. As the machine is constructed and operated, packages will pass through the heating and labeling devices regardless of whether or not the heating device is supplied with heat or the labeling device with labels. It is therefore possible to wrap articles in the manner described, heat seal the packages, and pass the sealed packages through the labeling device, applying or not applying a label as may be desired. It is also possible to pass the packages through the heating device without applying heat thereto, and then apply a band or label as they pass through the labeling device. The heat device, designated by the letter F, will next be described.

A shaft 340, journaled in the frames 134 and 136, has rigidly secured to its right hand end (as viewed in Fig. 13) the head casting 342, 35 having four lugs 344. To each of these lugs are bolted overhanging bars 346, spaced slightly away from the lugs by the nonheat conducting washers 348. Riveted to the bars 346, but spaced therefrom by the blocks 350, are plates 352. To each of the plates 346 and 352, are secured by screws 354, flat electrical heating elements 356, each having a terminal a' at one end and another b' at the opposite end. The object of spacing apart the bars 346 and the plates 352 is to 45 provide between them package receiving pockets 358. The spacers 350 have projections 360 at their inner ends, the object of which is to provide abutments 360 to limit the distance a package can be pushed into a pocket. This is necessary because, in this instance, the pockets are made wider than the thickness of a package and do not frictionally engage the sides thereof, as such frictional engagement would tend to displace, rearwardly, the turned over ends of the 50 wrapper as the package is pushed from the head E into a pocket of the heating device. The heating device rotates intermittently and in a counter-clockwise direction as viewed in Fig. 2a, and moves and dwells synchronously with the wrapping heads heretofore described. The shaft 340 is provided at its right hand end with Geneva and miter gear driving members, but as these driving members are exact duplicates of the driving members for the head E it is thought unnecessary to further describe them.

In order to maintain the necessary degree of heat in the bar 346 and the plate 352 it is desirable to cause a current of electricity to flow continuously through the heating elements 356 70 while they are moving as well as while they are dwelling. To accomplish this the following described connections are provided. To the frame 134 is bolted a bracket 362 bored for two fibre bushes 364. In these bushes are journaled two 75

shafts 366 to the ends of which are secured two blocks 368 and to these blocks are fastened two metal strips or brushes 370 and 372. The brush 370 rides on the outer surface of a metal ring 374 mounted on a fibre ring 376 surrounding shaft 340. The brush 372 rides on the outer surface of a metal ring 378 also mounted on the fibre bush 376. The two rings 374 and 378 are insulated from each other by the fibre ring 380. The fibre ring 376 and the two metal rings mounted thereto are caused to rotate with the heating device by a key pin 381 fitting in coinciding holes in the head casting 342 and the fibre ring. A conductor wire *a* is connected to the ring 378, and branches from this wire (not shown in the drawings), are led to each of the terminals *a'* of the heating elements. A conductor wire *b* is connected to the inner surfaces of the metal ring 374 and is led through a channel 382 cut in the fibre ring 376, and branches from this wire (not shown in the drawings), are led to each of the terminals *b'* of the heating elements. The brushes 370 and 372 are held firmly in contact with the metal rings 374 and 378 respectively by springs 384 connected to their outer ends and to the spring posts 386 held in fibre bushings 388 seated in the lugs 389 of the bracket 362. It will be evident that when wires are connected to the ends of the shafts 366 a closed circuit will be provided through which a current of electricity can flow continuously through all of the heating elements regardless of whether they are in motion or not.

The package pressing device, designated by the letter *G* in Figs. 2a and 16, comprises a disk 390, rigidly secured to the left hand end of the shaft 392, having bearings in the frames 134 and 136. The disk 390 is provided with eight lugs 394 to which are rigidly secured bars 396 as best shown in Fig. 18. Journalized in bearings in the disk 390 are eight shafts 398 to the left hand ends of which are secured arms 400. Each of these arms has right angled extending portions 402, approximately equal in length and width to the plates 396. Coiled springs 404, having one end pocketed in lugs 406 cast on the disk 390, and the other end pocketed in lugs 408 cast on the arms 400, tend to urge the extending portions 402 of the arms 400 towards the bars 396, to compress a package positioned between these two parts. The spaces between the bars 396 and extending portions 402 may, for convenience, be hereinafter referred to as package holding pockets. The projecting portions 402 are held away from the bars 396 when these parts are in package receiving position, against the resistance of the springs 404, by the arm 410 acting against the pins 412 driven into the lugs 408 of the arms 400. The arm 410 is rigidly secured to one end of the rock shaft 414, journaled for rocking motion in the bracket 416. To the other end of the rock shaft 414 is rigidly secured an arm 418 having at its lower end a cam roll 420 engaging the outer periphery of an open cam 422. The roll is held in close engagement with cam 422 by a coiled spring 424 attached to the lower portion of the arm 418. The shafts have collars 426 pinned to their right hand ends into which are driven stud pins 428, Figs. 16 and 18. The function of these pins will be later described. This pressing device rotates intermittently and in a counter-clockwise direction as viewed in Figs. 2a and 16, and has miter gear and Geneva drivers similar to those used to drive heads *E* and *F*, except that, in the present

instance, the Geneva wheel has eight slots, instead of four, as in the case of the Geneva wheels heretofore described. This is necessary, of course, because the package pressing device has eight package receiving positions.

The mode of operation of the heating and pressing devices will be readily understood. When a package has been carried by the head *E* to the station *S* the pusher finger 230 pushes the package into a pocket of the heating device which then carries it by two intermittent movements to the station *T*, the length of time required to carry the package from the station *S* to the station *T* being sufficient to cause the wax of the wrapper to be melted to the required degree. The pusher finger 232 then pushes the package from its pocket in the heating device onto a bar 396 of the pressing device. At this time the right angled extension 402 of the arm 400 is held spaced from the bar 396 by the cam 422 acting through the levers 410 and 418, to afford easy entrance of the package between the extension 402 and the bar 396. As soon, however, as the package has been positioned on the bar 396 the arm 410 moves out of engagement with the pin 412 and the spring 404 acting on the arm 400 causes the projecting portion 402 to bear on the package and hold it compressed between the said projecting portion and the bar 396. As it requires four rotary movements of the pressing device *G* to carry the package from the station *T* to the station *U* ample time is afforded for the melted wax of the wrapper to cool and seal together the overlapping peripheral portions of the wrapper and to seal the bent over end portions against the side of the package. The package is next delivered to the labeling device which will now be described.

To the table 6, Figs. 2a, 16 and 17, is bolted an upright frame or bracket 430 having bolted to its upper end a gear housing or box 432. Also bolted to the upper end of the bracket 430 is a support 434 for a magazine 436 in which labels are held in upright position in a stack. The labels are forced forwardly against flanges at the forward end of the magazine, one of which is shown at 438 Fig. 16, by means of a plunger head 449 which is pivotally mounted on the forward end of a horizontal stud 442 having its rear end secured in the lower end of a depending arm 444 carried by a horizontal rod 446. This rod is mounted to slide in a bearing 448 on the top of the gear box 432 and in another bearing in the vertical rod 450 the lower end of which is set into the bar 260 as shown in Fig. 15. The rod 446 is urged forwardly by means of a weight 447 connected with the rod by a cord 449 that passes over a suitably arranged guide pulley 451.

The labels are adapted to be fed one by one from the magazine, by means of a roll 452 which carries a segmental friction pad 454 for engagement with the label. The friction roll 452, at each revolution, delivers a label to a pair of feed rolls 456 which in turn feed the label between the rolls 458 which cooperate to feed it downwardly until its lower edge enters the notches 459 in the label support fingers 460. In this position the label is in the path of the packages as they are pushed from the pressing device at station *U*, through the labeling device. The label is guided during its downward passage from the upper to the lower feed rolls by upright guide members 453 carried by a bar 455 attached to the upright bracket 430. The feed rolls 458 are each provided with a series of spaced flanges 457, (Fig. 20) the flanges of one roll being opposite the spaces between the flanges 75

of the other roll and entering said spaces slightly.

The feed rolls 458 tend to feed the label downwardly into the notches 459 in the label support fingers, but the engagement thereof with the label 5 is so slight that when the lower edge of the label strikes the support 460 they effect no further appreciable feeding action on the label, they then merely serving to support the upper end of the label until it is engaged by a package, whereupon 10 the label is freely drawn from between the rolls and out of engagement with the label support fingers 460.

The friction roll 452 is carried on one end of a shaft 462, extending through and journaled in 15 the housing casting 432, Figs. 16, 17 and 20. A ratchet wheel 464 is mounted loosely on the shaft 462, and a gear 466 is riveted to its hub and is operatively engaged by a rack 468 which is mounted to slide vertically in bearings in the housing 20 casting 432, as best shown in Fig. 17. The ratchet wheel 464 is provided with a single notch that is adapted to engage a tooth on a pawl 470 pivotally mounted on an arm 472, the pawl being held toward the periphery of the ratchet wheel by a 25 spring 474 connected therewith. The arm 472 is rigidly secured on the shaft 462. With this construction, during the upward movement of the rack 468 the ratchet wheel 464 acts through the pawl 470 to rotate the friction roll carrying shaft 30 462 one complete revolution, the shaft being at rest during the downward movement of the rack.

The feed rolls 456 are driven with the friction roll 452, through a gear 476 riveted to the hub of the pawl carrying arm 472, and connected 35 through an idler 478 with a gear 480 which is secured on the shaft of one of the feed rolls 456, and engages a gear 482 secured on the shaft of the other feed roll. The shafts for the feed rolls 456 are journaled in the guide members 453 secured to the bar 455 attached to the upright frame 439. These shafts are driven by a gear 484 secured to the shaft of one of the feed rolls 456 through an idler 486 meshing with a gear 488 secured to the shaft of one of the rolls 458 and 40 meshing with a gear 490 secured to the shaft of the other roll.

The rack 468 extends downwardly through a hole in the table 6 and has its lower end connected by links 492 and 494 with one end of a cam lever 492 pivoted on the frame 4 and carrying a cam roll 494 that engages a groove in a cam 496 secured to the shaft 474.

The friction roll 452 is shown in Fig. 16 in the position it assumes when the roll is at rest, the friction pad of the roll being in engagement with the outer label in the stack and having carried the lower end of the label a sufficient distance out of the magazine to cause it to be engaged by the feed rolls 456. The label is in this position 50 when the package on which it is to be used is at the station W, Fig. 16. The driving mechanism for the presser head G and the label feed mechanism are so timed that just before the presser head G starts to move, to carry a package from the station W to the station U, a label is fed 55 downwardly into the notches of the supporting fingers 460 where it is in the path of the package as it is pushed from the presser head by the pusher finger 497, Fig. 2a. If for any reason, 60 there is no package in the presser head at station W, means are provided whereby the label feeding mechanism is made inoperable while a package holding pocket of the head G, moves from the station W to the station U.

55 Referring to Fig. 16, it will be observed that the

lever 498 pivotally mounted on the bracket 500 secured to the housing casting 432 has a portion adapted to engage the tail end of the pawl 470. To the other end of the lever 498 is connected a link 502 the lower end of which is connected to a lever 504 provided with a cam roll 506 engaging the periphery of a cam 508 secured to the shaft 304. A spring 510 connected to the lever 504 tends to hold the cam roll 506 in engagement with the cam 508. As a package holding pocket 10 of the presser head G approaches the station W the cam 508 lifts the lever 504 and consequently the right hand end of the lever 498. As has before been stated, the stud pin 428 is driven into a collar secured to one end of the shaft 398 to the 15 other end of which is secured the arm 400. It has also been stated that the arm 400 is rocked slightly by the lever 410 to move the projecting portion 402 away from the bar 396 to facilitate positioning a package on the bar 396 and to cause 20 the part 402 to bear on the package when it has been positioned on the said bar. It will be obvious that the stud pin 428 rocks or revolves through the same number of degrees as the arm 400. If there is a package in a pocket of the 25 presser head, as said pocket approaches the station W the arm 400 will be held at a greater distance from the bar 396 than is the case when there is no package in the pocket and, consequently, the pin 428 will be moved farther in a 30 counter-clockwise direction, viewing Fig. 16 than when there is no package in the pocket. In this case the end of the pin is in a position to prevent the right hand end of the lever 498 from moving down as far as it would otherwise be carried 35 by the action of the spring 510 and cam 508. In this position the lever 498 does not engage the pawl 470 and does not interfere with the operation of the label feeding mechanism. In case there is no package in a pocket of the presser head 40 as the pocket approaches the station W, the arm 400 being moved nearer the bar 396 the pin 428 does not engage the right hand end of the lever 498 by reason of which the spring 510 pulls this 45 end of the lever downwardly, causing the other end to engage the pawl 470 and prevent it from engaging the ratchet 464, thereby throwing the label feeding mechanism out of operation.

When a label has been delivered into the notches of the supporting fingers 460, and previously to the engagement of the package with the label, glue is applied to its forward side adjacent the lower edge thereof, by a glue roll 512 revolving in a glue pot 514 carried by the supporting member 516. This supporting member has an 50 outwardly extending arm 517 and is mounted for rocking motion on a shaft 518 carried by the bracket 520 secured to the table 6. The glue roll is moved to and away from engagement with the label by a link 522 connected at its lower end 60 with a forked member 524 carrying a cam roll 526 engaging peripheral surfaces of an open cam 528 secured to the shaft 474. The glue roll 512 is continuously rotated through the connections 65 illustrated in Figs. 17 and 19. A pulley (not shown) on the shaft 474 is connected by a belt with a pulley 530 secured to one end of the shaft 532 journaled in frame 439 and having secured to its other end a gear 534. The gear 534 meshes with an idler gear 536 which drives a gear 538 70 secured to one end of the shaft 540 journaled in an arm 542 extending upwardly from the supporting member 516. To the other end of the shaft 540 is rigidly secured a finger piece 544, Fig. 19a. The shaft 540 is concentric with the shaft 75

545 of the glue roll to one end of which is secured a gear 546 into which are driven pins 548 adapted to be engaged by the finger piece 544. This arrangement provides for driving the glue roll when the glue pot is positioned in the machine, but permits the easy removal of the pot for refilling, etc. Glue from the bottom of the pot is carried to the glue roll 512 by the distributor roll 550 driven by gear 552 secured to its outer end and meshing with the gear 546.

It will be observed that the label supporting fingers 460, an end view of which is shown in Fig. 16 and portions of which are shown in Fig. 19 are spaced somewhat apart. It will further be observed that the glue roll is provided with flanges 554 arranged opposite to the spaces between the supporting fingers. The plate 556 secured to a bar 558 secured to the frame 430 is provided with a series of depending fingers 560 which are opposite the label supporting fingers 460. When the glue roll 512 applies glue to a label, and the roll is retracted from glue applying position, the label is held from following the roll by the fingers 460 and 560.

25 When a label has been deposited on the supporting fingers 460, and glue applied to the lower edge of the label, the package is pushed from its pocket in the presser head G by the pusher finger 497, Fig. 2a across the plate 556 and between the bars 562 and 564 carrying the label therewith into a channel of the head H. As it is necessary to push the package a considerably greater distance from a pocket in the presser head G to a channel in the head H Fig. 2a than the longitudinal movement of the slide bar 202, the pusher finger 497 is secured to a block 566 mounted for sliding movement on the slide bar 202. The block 566 is connected by a link 568 to the upper end of a lever 570 pivotally mounted to the frame 4 and carrying at its lower end a cam roll 572 working in a groove in the cam 574 and rigidly secured to the shaft 304.

45 As the label stands on the supporting fingers 460 its upper end projects above the path of the package a distance slightly less than the width of a side of the package. When, therefore, the package and label have been pushed into a channel in the head H, and this head rotated 180°, the unused portion of the label will be hanging down across the mouth of the said channel, and when the package is pushed from the head H to the head J by the pusher finger 234, this portion of the label will be carried with the package into the pocket, thus completing the wrapping of the label about the package. As the head H and the means for driving it, are similar in all respects to the heads B, C and D it is thought unnecessary to describe it.

60 The head J is similar to the heads B, C and D except that it has eight lugs for attaching the channel forming bars and plates, and the Geneva wheel by which it is driven has eight slots. The bevel gears, however, that drive the Geneva arm, are so arranged that the head J will be driven in a counter-clockwise direction as viewed in Fig. 2a. When a package has been carried by the head J to the station Z it is pushed from its channel in the head by the pusher finger 236 on to a plate 580 secured to the upper end of a vertically reciprocating rod 582 (Figs. 34 and 35). The rod 582 is journaled in a bracket 584 bolted to the table 6 and is connected at its lower end by a link 586, Fig. 2a, to one arm of a bell crank 588. To the other arm of the bell crank is connected the link 590, to the lower end of which is secured a

forked member 592 carrying a cam roll 594 engaging the peripheral surface of a cam 596 secured to the shaft 474. As soon as the package has been pushed onto the plate 580, the plate is elevated by the cam 596, through the connections referred to, and lifts the package high enough so that it will be engaged by the latches 598. These latches are pivotally mounted on opposite sides of a package holding magazine and are urged to engaging position by the springs 599. This magazine comprises two channels 600 secured to a plate 602 bolted to a bracket 604 which in turn is bolted to the table 6. Slots cut in the sides of the channel 600 permit the latches 598 to project inside the magazine in position to engage and support the packages. During the upward movement of the plate 580 the latches are pushed outwardly by the package resting on the said plate but as soon as the package has been lifted to a level above the upper end of the latches the latches snap back into engaging position, being permitted to do this by slots 606 cut at opposite ends of the plate 580.

15 In order to adapt the machine for wrapping the rectangular articles shown in Fig. 22, it is only necessary to substitute the magazine illustrated in Fig. 5b. By providing the machine with the magazine illustrated in Fig. 5c it will be adapted to wrap the rectangular bar illustrated in Fig. 23. The machine can be adapted for 20 wrapping a plurality of bars, making a package of relatively greater thickness, as illustrated in Fig. 24, by providing it with the magazine illustrated in Fig. 5c and by slightly increasing the width of the channels in the various package 25 carrying heads throughout the machine.

30 Whenever the magazine for holding the candies to be wrapped becomes empty, it is desirable to clear it of partly wrapped and sealed packages. Referring to Fig. 2b, it will be observed that the pusher 182, for pushing a row of candies out of the magazine, and the rack 73 for operating the feed rolls, are both actuated by cams secured to 35 the shaft 80. Referring to Fig. 3, it will be observed that the horizontal shaft 212 drives all of the cam shafts of the machine except the shaft 80, so that as long as the shaft 212 is driven all parts of the machine will be operated except those 40 actuated by cams on the shaft 80. Figs. 1, 3, 36, 37 and 38 illustrate mechanism by means of which the shaft 80 can be driven from the shaft 206, in timed relation with the rest of the machine, or can be thrown out of operation at the will of the 45 operator. Rigidly secured to the shaft 206 is a spur gear 650 meshing with a similar gear 652 loosely mounted on the shaft 80. Rigidly secured to the shaft 80 is a clutch 654 provided with a square hole 655 in which a clutch bolt 662 is slidably carried. To the shaft 80, adjacent the clutch 654, is secured a collar 658. A coiled spring 660 pocketed in a hole in the clutch bolt 662, and bearing against the collar 658, urges the bolt in the direction of the gear 652. This gear has a 50 single pin 664 the head of which is in the path of the end of the bolt when the bolt is in the outward or engaging position. As long as the bolt is in the engaging position as shown in Fig. 38, the shaft 80 and the parts actuated thereby will be 55 driven in timed relation with the rest of the machine.

55 A bracket 666 bolted to the frame 2 has pivotally mounted thereon one end of a treadle 668, to the other or outer end of which is secured a 60

pedal 670. Midway of the treadle is pivotally connected a link 672, having secured to its upper end the clutch latch 674. This latch has a downwardly extending stem to which the upper end 5 of the link 672 is connected. The stem of the latch is seated, for vertically reciprocating motion, in a pocket formed in the bracket 676 bolted to the frame 2. Surrounding the stem of the pocket latch 674 and seated on the bottom of the pocket 10 in the bracket 676, a coiled spring 673 presses against a shoulder on the stem of the latch, urging the latch in an upward direction, and by reason of the link 672 being connected to the treadle 668, the treadle is also urged upwardly 15 by this spring. When the treadle 668 is pressed downwardly it is caught and held in this down position by the latch 689 pivotally mounted on the bracket 682 and urged to locking position by the spring 684 pocketed at one end in the latch 20 680 and at the other end in a lug 686 on the bracket 682. When the treadle is in the down position the latch 674 and clutch bolt 662 are in the positions shown in Fig. 38 which shows the bolt in engaging or driving position. When 25 it is desired to stop the operation of the parts actuated by cams on the shaft 89, the operator presses on the extending arm 688 of the latch 680 which causes it to release the treadle and the spring 678 raises the latch 674 to the position 30 shown in Fig. 37. The segmental portion of the clutch latch is bevelled off at the end facing the clutch bolt as the latter revolves in the direction of the latch. The clutch bolt has a notch cut in its underside, as viewed in Fig. 38, which is 35 of greater width on the rear face. It will be readily understood, therefore, that when the latch 674 is in the high position its tapered edge will enter the notch in the latch and force the latch to disengaging position.

40 In order that the shaft 89 and parts operated therefrom may not overrun, a brake 690 is provided to act on the peripheral surface of the clutch 654. One end of this brake is secured to a stud 692 carried by bracket 694 bolted to the frame 2. The other end of the brake is riveted 45 to a lug of the casting 696 secured to the upper end of the rod 698 pivotally connected at its lower end to the treadle 668. It will be readily seen that when the treadle is disengaged from 50 the retaining latch 680 it will be urged upwardly by the spring 678 and the resulting upward movement of the rod 698 will cause the brake band to be drawn tightly around the peripheral surface of the clutch resulting in the instant stoppage of the shaft 89.

55 As will be evident to those skilled in the art my invention permits various modifications without departing from the spirit thereof or the scope of the appended claims.

60 What I claim is:

1. A machine for wrapping articles of the class described having, in combination, a wrapping device provided with spaced apart members to receive an article and its wrapper at one station, 65 means for positioning an article and its wrapper between the said spaced apart members, means for rotating the wrapping device whereby the article and its wrapper are carried to a second station, a second wrapping device provided with 70 spaced apart members to receive the article and its wrapper at the second station, means for rotating the said second wrapping device whereby the article and its wrapper are carried to a third station, a third wrapping device provided with 75 spaced apart members to receive the article and

its wrapper at the third station, means for pushing the article and its wrapper from the first wrapping device to the second, and similar means for pushing the article and its wrapper from the second wrapping device to the third, said pushing means being adapted to crimp the ends of the wrapper at opposite side of the article as the article and its wrapper are being pushed from one wrapping device to the next. 5

2. A machine for wrapping articles of the class 10 described having, in combination, means for winding wrappers about the articles, means for closing the wrappers over the ends of the articles to form packages, an intermittently rotating device provided with a plurality of package holding 15 means for receiving successively at one station the packages thus formed, means for successively positioning the packages in the holding means, means for intermittently rotating the said device whereby the packages are carried step by step 20 from the first station to a second station, means at the second station for successively ejecting the packages from each holding means and pushing them to a subsequent station, means at the subsequent station for winding a second wrapper 25 about each package, means for feeding a second wrapper across the path of each package whereby it is carried with the package to the wrapping means, and means operated by each package holding means whereby the means for feeding 30 the second wrapper is rendered inoperative when a package holding means without a package therein approaches the said second station.

3. In a machine for wrapping a plurality of disk like articles, a horizontal support for the 35 articles to be wrapped, a wrapping means provided with a pocket in alignment with the said support to receive a row of the articles and their wrapper, a plurality of vertical guideways above the horizontal support having open lower ends 40 spaced a distance therefrom slightly greater than the thickness of one of the articles, each of the said guideways being adapted to hold in vertical alignment a stack of the articles with the stack resting on the said horizontal support the said 45 stacks in the said guideways being slightly spaced apart, a pusher member adapted to push the lowermost row of articles from beneath the said stacks into the pocket of the wrapping means, the said pusher member being provided with flaring 50 forwardly projecting portions whereby the end-most articles of the row are moved inwardly to close the spaces between the articles as the row is pushed toward the wrapping means. 55

4. In a wrapping machine for wrapping a plurality of disk like articles, a horizontal support for the articles to be wrapped, a wrapping means provided with a pocket in alignment with the said support to receive a row of the articles and their wrapper, a plurality of vertical guideways 60 above the horizontal support having open lower ends spaced a distance therefrom slightly greater than the thickness of one of the articles, each of the said guideways being adapted to hold in vertical alignment a stack of the articles with the stack resting on the said support the said 65 stacks in the said guideways being slightly spaced apart, a pusher member adapted to push the lowermost row of articles from beneath the said stacks into the pocket in the wrapping means, the said pusher member being so formed that as the articles are pushed forward the end-most articles are moved inwardly to close the spaces between the articles. 70

5. A machine for wrapping articles of the class 75

described, having in combination, an intermittently rotating device provided with a plurality of article holding means for receiving successively at a receiving station the articles to be wrapped, means for successively positioning articles in the holding means at the receiving station, means for intermittently rotating said device whereby the articles are carried step by step from the said receiving station to a discharging station, means beyond the discharging station for winding a wrapper about each article, means at the discharging station for successively ejecting the articles from each holding means and pushing them into the wrapping means, means for feeding a wrapper across the path of each article as the article is pushed from the holding means to the wrapping means whereby the wrapper is carried with the article to the wrapping means, and means operated by each article holding means whereby the means for feeding a wrapper is rendered inoperative when an article holding means without an article therein approaches the discharging station.

6. A machine for wrapping articles of the class described, having in combination, means for winding wrappers about the articles, means for closing the wrappers over the ends of the articles to form packages, an intermittently rotating device provided with a plurality of package holding means for receiving successively at a receiving station the packages thus formed, means for successively positioning the packages in the holding means at the receiving station, means for intermittently rotating said device whereby the packages are carried step by step from the said receiving station to a discharging station, means beyond the discharging station for winding a second wrapper about each package, means at the discharging station for successively ejecting the packages from each holding means and pushing them into the wrapping means, means for feeding a second wrapper across the path of each package as the package is pushed from the holding means to the wrapping means whereby the wrapper is carried with the package to the wrapping means, and means operated by each package holding means whereby the means for feeding a second wrapper is rendered inoperative when a package holding means without a package therein approaches the discharging station.

7. A wrapping machine of the class described, having in combination, a rotary member, a plurality of article holding devices carried by the rotary member, means for intermittently driving the rotary member whereby the article holding devices are moved step by step from an article receiving station to an article discharging station, a wrapping means beyond the discharging station for applying a wrapper to each article, means at the discharging station for pushing the article from each article holding means into the wrapping means, means for feeding a wrapper across the path of each article as the article is pushed from the holding means to the wrapping means whereby the wrapper is carried with the article into the wrapping means, each of the said package holding devices comprising a jaw rigidly secured to the rotary member and another jaw pivotally mounted on the rotary member whereby it is adapted to be moved away from the first mentioned jaw while an article is being positioned thereon, and then toward the first mentioned jaw to hold the article so positioned in place, means for actuating the second mentioned jaw, and means made effective by the motion of the said second mentioned jaw whereby the wrapper feeding means is rendered inoperative when a package holding means without a package therein approaches the discharging station.

8. A machine for wrapping articles having, in combination, means for wrapping an article when an article and a wrapper are presented thereto, a horizontal support for the articles to be wrapped, a vertical guideway above the horizontal support having an open lower end spaced a distance therefrom slightly greater than the thickness of one of the articles, the said guideway being adapted to hold in vertical alinement a stack of the articles with the stack resting on the said horizontal support, means for feeding an article from the bottom of the stack into the said wrapping means, means for feeding a wrapper across the path of the article whereby the wrapper is carried with the article into the wrapping means, and means whereby the said article feeding means and the said wrapper feeding means may be rendered inoperative independently of the said wrapping means.

HARRY E. TOWNSEND. 50
